Inventor:

George Nelson
by his attorney

J. W. Hollister

United States Patent Office.

GEORGE NEILSON, OF BOSTON, MASSACHUSETTS.

Letters Patent No. 75,566, dated March 17, 1868.

IMPROVEMENT IN LAMP-BURNERS.

The Schedule referred to in these Letters Patent and making part of the same.

TO WHOM IT MAY CONCERN:

Be it known that I, GEORGE NEILSON, of Boston, in the county of Suffolk, and State of Massachusetts, have invented certain new and useful Improvements in Lamp-Burners; and I hereby declare the following to be a full, clear, and exact description of the same, reference being had to the accompanying drawings.

My invention refers to that class of burners in which the deflector is elevated some distance above the chimney-rest and base, so as to allow light to pass out from beneath the deflector; and its object is to adapt a burner of this description to be used either with or without a larger glass or globe surrounding the ordinary chimney. To this end my invention consists essentially of the combination, with a burner in which the base or chimney-rest is combined with an elevated deflector, as specified, of a globe-frame or supporter adjustable upon or permanently united with the said chimney-rest, as hereinafter described. By thus adapting the burner to receive a globe, I am enabled, with little or no trouble and expense, to produce a lamp which will give a mellow and soft light, and which may be made to present a highly ornamental appearance.

To enable others skilled in the art to understand and use my invention, I will now proceed to describe the manner in which the same is or may be carried into effect by reference to the accompanying drawings, in which—

Figure 1 represents an elevation of a lamp-burner from which the globe-frame has been removed.

Figure 2 is a vertical central section of the same; and

Figure 3 is a top view of the globe-frame detached.

The burner I have represented in illustration of my invention is one for which Letters Patent of the United States have been recently granted me, and it needs, therefore, no detailed description at this time. It belongs to that class of burners hereinbefore mentioned, in which the base or chimney-rest *a* is combined with an elevated deflector, *b*. The chimney, when placed upon the burner, rests on the chimney-seat *a*, while it is supported by the springs *c* and the elastic rim of the deflector-rest or frame *d*. In order to combine with this burner a frame, upon which a globe can be supported, I form upon the periphery of the chimney-rest, a seat, *f*, which can be either made separately, and then attached to the chimney-rest, or struck up in one piece with the latter from the sheet metal of which they both are composed. The seat *f*, thus formed, has a slightly bevelled surface, so that when the detachable or adjustable globe-frame *h* is pressed down on the same, the two will be wedged and held firmly together. A flange or shoulder, *i*, which projects laterally from the lower end of the seat *f*, prevents the globe-frame from slipping too far down upon the seat. This globe-frame or holder *h*, as shown in the drawings, has an annular form, and consists of two parts, the globe-rest *k*, upon which the base of the globe is held, and a hoop or collar, *l*, which is of such size as to fit closely around the seat *f*. The frame, however, may be constructed in any other suitable manner.

I would further remark that the globe-frame can be either detachable or united solidly with the chimney-rest, of which it will in such case, form part, and it may be either struck up in one piece with the chimney-rest, or made separately, and afterwards secured in proper position upon the chimney-rest.

Having now described my invention, and the manner in which the same is or may be carried into effect, what I claim, and desire to secure by Letters Patent, is—

The combination, with a lamp-burner in which the base or chimney-rest is combined with an elevated deflector, as herein specified, of a globe-frame, adjustable upon or permanently united with the said chimney-rest, substantially in the manner and for the purposes shown and set forth.

In testimony whereof, I have signed my name to this specification before two subscribing witnesses.

GEORGE NEILSON.
